UNITED STATES PATENT OFFICE.

GEORGE A. MELLON, OF ST. LOUIS, MISSOURI, ASSIGNOR TO LINK-FABRIC COMPANY OF AMERICA, OF ST. LOUIS, MISSOURI, A CORPORATION.

CORNER-FASTENING FOR BEDSTEADS.

1,064,357.

Specification of Letters Patent. Patented June 10, 1913.

Application filed December 14, 1912. Serial No. 736,696.

To all whom it may concern:

Be it known that I, GEORGE A. MELLON, a citizen of the United States of America, and a resident of the city of St. Louis and State of Missouri, have invented certain new and useful Improvements in Corner-Fastenings for Bedsteads, of which the following is a full, clear, and exact description, reference being had to the accompanying drawings, forming a part of this specification.

My invention relates to a corner fastening for metallic bedsteads, including hollow corner posts and side rails, and it has for its object to provide a simple corner fastening for a bedstead of this kind, in which the brackets commonly applied to the corner posts are dispensed with, this being accomplished by furnishing the bedstead posts with keyhole slots formed directly therein, and providing the side rails with headed members which are inserted through the keyhole slots and which are, due to peculiar formation of the parts, capable of being drawn tightly to furnish a close and firm joint between the side rails and posts.

Figure I is in part a horizontal section of a bedstead post, and in part a top or plan view of a fragment of a side rail fitted to said post, illustrating my invention. Fig. II is a vertical cross section taken on line II—II, Fig. I, through the side rails shown in Fig. I, with a fragment of the corner post shown in elevation, and joint forming members illustrated in dotted lines. Fig. III is in part a vertical section taken on line III—III, Fig. I and in part a vertical section through the body of the side rail fastening piece on a line immediately in front of the lug projecting from said body. Fig. IV is a perspective view of a fragment of the corner post showing the keyhole slot therein. Fig. V is a perspective view of the corner fastening member of the side rail.

In the accompanying drawings: 1 designates one of the hollow corner posts of a metallic bedstead, there being four of such posts used in the bedstead, as usual, and all being provided with similar structural features, in so far as my invention is concerned. 50 In the corner post is a keyhole slot 2 that is enlarged midway of its top and bottom, as seen at 3, to permit the passage through

the slot of head members of a side rail fastening piece.

The post 1 is provided with an inclined 55 wall 4, located interiorly of the post, and extending downwardly and inwardly toward the center of the post from the enlargement 3. The inclined wall 4 is preferably produced by indenting the post at the point 60 named, as clearly shown in Figs. III and IV, and the object of furnishing such inclined wall within the post will be hereinafter made apparent.

A designates the side rail of a bedstead 65 fitted to the post 1. This side rail is provided with a fastening piece 5, having an end face 6, which corresponds in contour to the corner post, whether said post be circular in form, as shown, square in form, or of 70 any other desired shape, in cross section. The fastening piece 5 is provided with a lug 7, extending from its face 6, adapted to be introduced through the slot 2 in the corner post. This lug 7 is furnished with a head, of 75 any suitable construction, but preferably formed of extensions 8, that project laterally from the lug, and are adapted to pass through the enlargement 3 of the slot 2 when the corner piece 5 of the side rail is applied 80 to the corner post 1. When the corner piece of the side rail is fitted to the corner post 1, the lug 7 passes through the slot 2, and the head thereof becomes positioned within the corner post beyond its inner wall; and upon 85 the side rail being moved downwardly, the head of the lug rides against the inclined surface 4, whereby the face 6 of the corner fastening piece 5 is drawn tightly against the outer face of the corner post to effect a 90 tight joint between the corner fastening piece of the side rail and the corner post.

To facilitate the production of a tight joint between the fastening piece of the side rail and the corner piece, the head of the lug 95 7 is inclined forwardly from both the bottom and top of the head toward the vertical center of the head. By thus forming the head of the lug 7, I furnish inclined planes at its front face, either of which may ride in 100 contact with the inclined wall 4 at the interior of the corner post 1, in effecting a tight joint between the side rail and the post, and the double incline makes it possible for

the side rail to be applied to the corner post, in reversed positions.

I claim:—

5 In a bedstead, a hollow corner post having a slot therein, the post being indented to provide internal, downwardly inclined faces alongside said slot, and a side rail having

a fastening piece provided with a lug having a terminal head engaging said inclined faces to draw the side rail toward said post.

GEORGE A. MELLON.

In the presence of—

A. J. McCauley,

E. B. Linn.
